UNITED STATES PATENT OFFICE.

CHARLES B. CLARK, OF BUFFALO, NEW YORK.

DESIGN FOR GATE-HINGE.

Specification forming part of Design No. 7,238, dated March 10, 1874; application filed February 13, 1874.
[Term of Patent 14 years.]

G.

To all whom it may concern:

Be it known that I, CHARLES B. CLARK, of Buffalo, in the county of Erie and State of New York, have invented a Design for a Gate-Hinge, of which the following is a specification:

The nature of my design is fully represented in the accompanying illustration, to which reference is made, in which—

Figure 1 is a view of the upper hinge, shown connected together; and Fig. 2, a view of the lower one, shown disconnected.

As shown in Figs. 1 and 2, A C are the double-eyed portions of the hinges, which are attached to the post, and B D are the single-eyed portions, which are attached to the gate. The bases of each half of the upper hinge and of one-half of the lower hinge are formed rectangular at the part from which the hubs or eyes *h h'* project, and the remaining portion is reduced in width by converging curves *f f* merging into parallel sides *i i*, which are terminated abruptly by the right angles *k k*, the remaining or intermediate extended portion being of semicircular form *g*, which merges into the angles *k k* by short curves, as shown.

The base of the half C of the lower hinge corresponds in design with that of the other portions, except that a large portion of the central extension is dispensed with, and in its place a lug or projection, *l*, is formed at right angles with the plane of the base.

The base of each portion of the hinge is ornamented with a raised bead or rib, *m m*, surrounding the margin, which gives an appear-

ance of relief to the hinge, and, in connection with the symmetrical form of the base, has a very artistic effect.

In the double-eyed portions of the hinge the ribs *n n*, which proceed from the hubs *h h*, are so formed that their inner or proximate faces are straight and in a line with the proximate faces of the hubs *h h*, as shown in Figs. 1 and 2, while their outer faces extend to the outer faces of the hubs by a gradual curve, as shown, while the ribs upon the opposite half are situated centrally, as usual.

This form of the parts gives to the hinge a varied and agreeable appearance.

I claim as my invention—

1. The design for a gate-hinge consisting of a base rectangular at the eye side, with curves *m m*, which converge into parallel planes *i i*, the latter terminating in abrupt angles *k k*, which are united by a semicircular convex curve, *g*, the whole surrounded with a marginal bead, substantially as shown and described.

2. In the double-eyed portion, the formation of the ribs *n n* with parallel proximate faces, and the outer faces curved gradually, inward from the hubs, substantially as shown and described.

In witness whereof I have hereunto signed my name in the presence of two subscribing witnesses.

CHAS. B. CLARK.
